SEWING MACHINE

Philip S. Egan, Glenview, Ill., assignor to Sears, Roebuck
and Co., Chicago, Ill., a corporation of New York

Application September 23, 1957, Serial No. 47,818

Term of patent 14 years

(Cl. D70—1)

FIG. 1

FIG. 2

FIG. 3

FIG. 4

FIG. 5

Fig. 1 is a front and end perspective view of a sewing machine embodying my new design;

Fig. 2 is a rear perspective from the opposite end from that of Fig. 1;

Fig. 3 is a top perspective view thereof, and

Figs. 4 and 5 are end perspective views taken from opposite ends of same.

I claim:

The ornamental design for a sewing machine, as shown.
